UNITED STATES PATENT OFFICE.

STANISLAW SALA, OF DETROIT, MICHIGAN.

SAFETY MILK-BOTTLE AND MAIL RECEPACLE.

1,218,477.

Specification of Letters Patent.

Patented Mar. 6, 1917.

Application filed June 22, 1916. Serial No. 105,164.

To all whom it may concern:

Be it known that I, STANISLAW SALA, a subject of the Emperor of Austria-Hungary, residing at Detroit, in the county of Wayne 5 and State of Michigan, have invented certain new and useful Improvements in Safety Milk-Bottle and Mail Receptacles, of which the following is a specification.

This invention relates to certain new and 10 useful improvements in safety milk bottle and mail receptacles.

The primary object of the invention is the provision of a receptacle adapted for the reception of different forms of mail matter 15 as well as packages such as milk bottles, all of the goods being securely retained against extraction from outside of the building although readily released from a point within the building.

20 A further object is to provide a mail box having mail receiving slide members automatically locked against withdrawal when closed and simultaneously releasable, one of the said slide members having a constantly 25 open mail receiving slot therein.

The invention contemplates a casing having separate flat mail and package mail receiving slides arranged for movements in planes perpendicularly arranged, separate 30 ejecting means being provided therefor as well as simultaneous releasing means, the device also having a closable bottle receiving compartment, the releasing means thereof being adjacent the releasing means for the 35 mail slides both of which are operable from a point within a building or wall upon the exterior of which the device is mounted.

With these general objects in view and others that will appear as the nature of the 40 invention is better understood, the same consists in the novel construction, combination and arrangement of parts hereinafter more fully described, illustrated in the accompanying drawings, and then claimed.

45 In the drawings forming a part of this application and in which like designating characters refer to corresponding parts throughout the several views:—

Figure 1 is a front elevation of the device. 50 Fig. 2 is a rear elevation thereof with a portion of the rear plate removed.

Figs. 3 and 4 are transverse sectional views taken upon lines III—III and IV—IV respectively, of Fig. 5.

55 Fig. 5 is a central vertical longitudinal sectional view through the device.

Fig. 6 is a perspective view of the flat mail receiving slide detached.

Figs. 7 and 8 are perspective views of the locking levers for the milk bottle holder. 60

Fig. 9 is a similar view of one of the locking levers for the mail receiving slides.

Fig. 10 is a perspective view of a portion of the package mail receptacle, and,

Fig. 11 is a perspective view of one of the 65 releasing means of the device.

The invention broadly consists of a substantially rectangular casing 10 adapted to be permanently secured to a wall 11 such as a house wall with a back plate 12 of the 70 casing flatly positioned thereagainst, the said casing having a forwardly arranged milk bottle receiving compartment 13 and a chamber 14 positioned rearwardly thereof for receiving a comparatively flat slide 15 75 adapted for the reception of flat mail matter, a slide or drawer 16 being arranged within a bottom chamber 17 of the casing and adapted for the reception of mail packages.

The top or roof 18 of the casing 10 is forwardly sloping, the chamber 14 being open at its top as at 19 for the reception of the said flat slide 15 which latter has a narrow mail receiving slot 20 in its upper inclined 80 end 21 which is in the form of a plate adapted to overlie the adjacent portions of the casing top 18. A cut-away portion or open window 22 is provided in the forward wall 23 of the slide 15 adapted to substantially 85 align with a transparent window 24 arranged in the inner wall 25 of the milk bottle compartment 13 while a swinging door 26 is arranged for closing the forward side of the compartment 13 having a glass 90 window 27 therein, the said door being operable by means of a handle or knob 28, and a spring 36 being provided to slightly open the door 26 automatically when released.

Locking levers 29 and 30 right angular 100 in form are pivoted at the angle portions 31 thereof beneath the bottom 32 of the compartment 13 and chamber 14 and between the said bottom 32 and a false or intermediate bottom 33 arranged parallel 105 thereto and mid-way between the main bottom 32 and the top 34 of the lower chamber 17 of the casing 10.

A spring 35 connects the levers 29 and 30 together normally maintaining upright 110 locking lugs 36 upon the free ends of the said levers inwardly positioned and within

the inward path of movement of oppositely positioned engaging hooks 37 carried upon the inner side of the door 26 adjacent the bottom thereof and arranged inwardly of the compartment 13 when the door is closed.

5 The rear portions or arms of the levers 29 and 30 are complementally formed one of the same having a V-shaped recess 38 for the reception of the V-shaped end 39 of the 10 adjacent arm.

10 A releasing member 40 of the form best illustrated in Fig. 11 is arranged for outwardly moving the lugs 36 against the action of the spring 35 and consists of a pin 41 15 slidably arranged through a perforation 42 in the back plate 12 of the casing 10 and having a substantially cubical head 43 normally engaged by the inner contacting end portions of the arms of the said levers 29 and 30.

20 It will be understood that when the levers 29 and 30 are normally arranged as shown in Fig. 4 of the drawings, a closing of the door 26 brings the hooks 37 into engagement with the lugs 36 while an inward impulse exerted 25 upon the pin 41 from the inner side of the wall 11 effects a pivotal movement of the levers 29 and 30 moving the lugs 36 outwardly as indicated by dotted lines in Fig. 4 of the drawings and releasing the lugs 36 30 from the hooks 37.

Similar levers 44 and 45 are arranged between the false bottom 33 and the chamber top 24 having angular downwardly extending locking lugs 46 within the paths of 35 movement of hooks 47 carried by the front wall 48 of the aforementioned slide 16. The levers 44 and 45 are connected together by a spring 49 being pivotally mounted similar to the levers 29 and 30 and having a releasing 40 means consisting of a pin 50 slidably extending through the casing plate 12 and the wall 11, being provided with a head 51 whereby the rear portions of the levers 44 and 45 may be forced inwardly for releasing 45 the lugs 46 from the hooks 47, it being understood that the spring 49 normally maintains the said lugs 46 in their locked engagement with the hooks 47. A leaf spring 52 is arranged upon the rear wall 53 50 of the slot 16 and engages the casing plate 12 for moving the slide 16 forwardly to its open position when released by means of the pin 50. A downwardly extending hook 54 is centrally carried by the slide 15 freely passing through the compartment bottom 32 and the false bottom 33 and engaging beneath the rear arm or portion of the pivoted lever 44. The inward releasing movement of the lever 44 disengages the rear arm thereof 60 from the hook 54 allowing a leaf spring 55 positioned beneath the slide 15 to move the latter slightly upwardly through the chamber opening 19 in the top of the casing. The door 26 and receiving slides 15 and 16 are 65 normally in their released open positions.

The milk vender may then open the door 26, insert a bottle of milk within the compartment 13, and upon closing the said door the same is retained in its locked position by means of the lever lugs 36 releasable from 70 the interior of the house by means of the push pin 41. Packages of mail may be placed within the bottom slide 16 and the slide then closed which engages the locking lugs 46 with the hooks 47 thereof for locking the 75 slide in its closed position. Flat mail matter such as letters and cards are readily positioned within the slide 15 through the top receiving slot 20 thereof and the said slide 15 normally being slightly elevated resiliently mounted upon the spring 55, the said slide is depressed after the mail matter has been inserted therein until the hook 54 which is of resilient material passes downwardly over the adjacent arm of the lever 44 until 80 the said hook rests in locked position therebeneath. While the slot 20 remains constantly open, it would be extremely difficult to extract mail matter therefrom by reason of its contracted form while upon inwardly 85 moving the releasing pin 50, the hook 54 is released and the spring 55 forces the slide 15 upwardly so that a person may readily remove the slide 15 entirely from the chamber 14 and readily remove the mail from the 90 slide through the open window 22 thereof. When the slide is in its locked position, the presence of mail matter therein may be readily determined by looking through the door window 27, the compartment window 100 24 and the slide window 22. A receiver for flat mail and mail packages is thus arranged having separate movements in perpendicular directions each being automatically partially projected upon the operation of the single 105 releasing pin 50.

While the present form of the device is believed to be preferable, it will be understood that minor changes may be made if desired.

110 What I claim as new is:—

1. A device of the class described comprising a casing having a chamber therein open at the top of the casing, a mail receiving slide removably arranged within the said chamber having a contracted mail receiving slot in the upper end thereof and a mail exit in its forward wall, an ejecting spring for the said slide, and releasable locking means for the slide.

2. A device of the class described comprising a casing having a chamber therein open at the top of the casing, a mail receiving slide removably arranged within the said chamber having a contracted mail receiving slot in the upper end thereof and a mail exit in its forward wall, an ejecting spring for the said slide, a transparent window in the said casing adjacent the said exit, a mail receiving slide arranged in the 130

bottom of the said casing having a path of movement at right angles to the vertically movable slide, locking means for the said slides, and a releasing means for the said locking means.

3. A mail receptacle comprising a casing having a vertically arranged chamber therein open at the top of the casing and a bottom chamber open at the front of the casing,
10 mail receiving slides shiftably arranged within the said chambers, interlocking engageable locking levers pivoted within the said casing between the said chambers, keepers for the said locking levers carried by
15 the said slides, and operating means for the said levers whereby the said slides are simultaneously released.
4. A mail receptacle comprising a casing having a vertically arranged chamber therein open at the top of the casing and a bottom chamber open at the front of the casing, mail receiving slides shiftably arranged within the said chambers, interlocking engageable locking levers pivoted within the
20 said casing between the said chambers, keepers for the said locking levers carried by the said slides, operating means for the said levers whereby the said slides are simultaneously released, the said vertically mova-
25 ble slide having a forward opening therein,

a swinging door provided for the front wall of the said casing, transparent windows within the said door and adjacent wall of the said vertical chamber forwardly of the said slide opening, locking levers for the 35 said door, and releasing means for the said levers positioned adjacent the aforementioned releasing means.

5. A device of the class described comprising a casing, separate vertically and 40 horizontally movable mail receiving slides carried by the said casing, ejecting springs for the said slides, retaining means for the said slides when retracted, and releasing means for the said retaining means operable 45 at a distance rearwardly of the said casing.

6. A device of the class described comprising a casing having vertically and horizontally movable separate mail receiving slides and a bottle receiving compartment 50 adjacent the said slides, means for obtaining visual access to the vertically movable slide through the said casing compartment, a closure door for the said compartment, retaining means for the said slides and door, 55 and releasing means for the said retaining means operable rearwardly of the said casing.

In testimony whereof I affix my signature.
STANISLAW SALA.
